J. F. HEMENWAY,
AUTOMATIC PRESSURE RELEASE FOR CLOTHES WRINGERS.
APPLICATION FILED SEPT. 9, 1916.

1,250,171.

Patented Dec. 18, 1917.

UNITED STATES PATENT OFFICE.

JOHN F. HEMENWAY, OF NEW YORK, N. Y.

AUTOMATIC PRESSURE-RELEASE FOR CLOTHES-WRINGERS.

1,250,171.

Specification of Letters Patent. Patented Dec. 18, 1917.

Application filed September 9, 1916. Serial No. 119,177.

To all whom it may concern:

Be it known that I, JOHN F. HEMENWAY, a citizen of the United States, residing at New York city, in the county of New York 5 and State of New York, have invented certain new and useful Improvements in Automatic Pressure-Releases for Clothes-Wringers, of which the following is a specification, reference being had therein to the accompanying drawing.

This invention relates to automatic pressure release for clothes wringers, the object being to provide a clothes wringer with a pressure releasing device which will operate 15 automatically in case of a foreign object being drawn between the pressure rolls so as to instantaneously release the pressure thereon.

Another object of my invention is to provide an automatic pressure release which is exceedingly simple and cheap in construction and one which can be readily applied to the ordinary form of clothes wringer now in use.

Another object of my invention is to provide a pressure release in which a pivoted latch is employed for holding the movably mounted top bar carrying the pressure screws in predetermined position within the 30 frame, said latch being released by the upward movement to the upper pressure roll.

Other and further objects and advantages of the invention will be hereinafter set forth and the novel features thereof defined by the 35 appended claims.

In the accompanying drawings,

Figure 1 is a side elevation of a clothes wringer partly in section showing the application of my improved construction of automatic pressure release thereto;

Fig. 2 is an end view of the same;

Fig. 3 is a top plan view; and

Fig. 4 is a detail perspective view of the supporting plate and pivoted latch.

Like numerals of reference refer to like parts in the several figures of the drawing.

In the drawing, 1 indicates the frame of an ordinary construction of clothes wringer which is provided with the usual slotted side bars 2 in which are mounted bearings 3 and 4 carrying shafts 5 and 6, provided with pressure rolls 7 and 8 which are preferably provided with meshing gears inclosed by gear casings 9. Mounted on the top of the bearings 4 is a pressure bar 10 which is preferably secured to the gear casings 9, and

when the bearings are moved upwardly, the gear casings will be raised at the same time so as to allow free movement of the upper pressure roll. 60

Slidably mounted within the slotted portions of the side bars 2 of the wringer frame, is a bar 11 which carries a bowed pressure spring 12, the ends of which engage the ends of the pressure bar 10 over the bearings 4, as clearly shown in Fig. 1. Slidably mounted within the upper portion of the side bars of the wringer frame is a top bar 13 which is slidably connected to the bar 11 by screws 14 which work in bores 15 formed in the bar 11 as clearly shown in Fig. 1 in order to allow the top bar to move independent of the bar 11 for the purpose hereinafter fully described.

The top bar 13 is provided with threaded boxes 16 at each end in which are mounted pressure screws 17, the lower ends of which engage bearings 18 secured in the top of the bar 11 as clearly shown in Fig. 1 so that when the pressure screws are adjusted, the 80 pressure rolls will be placed under the proper tension in order to wring the clothes as they pass between the same.

Secured over the upper end of each of the side bars is a plate 19 which is provided with offset apertured ears 20 at its lower end which extend into the slot of the side bar and between which is pivotally mounted the offset apertured eye 21 of a pivoted latch 22 adapted to extend over the upper edge 90 of the plate and engage a wear plate 23 secured to the top of the top bar in order to hold the top bar in predetermined position within the wringer frame so that the pressure screws can be adjusted in order to exert 95 the desired pressure upon the pressure rolls.

Arranged over each end of the upper pressure roll carrying shaft 6 is a cap 24 so constructed that the shaft is free to rotate therein, said cap having a vertically disposed 100 channel stem 25, the web of which is cut away and the upper ends enlarged and rounded to form cam portions 26 adapted to coöperate with cam lips 27 formed on the sides of the pivoted latch 22 so that when 105 the upper pressure roll is moved a predetermined distance, the pivoted latches will be drawn outwardly out of the path of the top bar so as to allow the top bar to move vertically to release the pressure on the pressure rolls. The upper portion of the stem 25 is mounted in guide lugs 28 formed on the 110

plate 19 as clearly shown in Fig. 2 and the pivoted latches are engaged by the free ends of the bowed springs 29 secured to the web of the stem below the cutout portion so that 5 the pivoted latches are normally held in the path of travel of the top bar so as to hold the same in its proper position within the wringer frame so that the pressure screws carried thereby can be adjusted so as to adjust the pressure means.

In the construction of wringer herein shown to which I have applied my improved construction of automatic pressure release, I show pressure means in the form of a bowed 15 spring, but it is, of course, understood that the ordinary form of coil springs could be used, and I do not wish to limit myself to any particular construction of clothes wringer, as my invention is capable of being applied to any form of clothes wringer in which a movably mounted top bar is employed carrying pressure screws for adjusting the pressure means.

In the construction of pivoted latch and 25 the releasing member herein shown carried by the upper pressure roll carrying shaft, I have shown the stem bifurcated at its upper end to receive the pivoted latch which works between the furcations thereof and is provided with cam lips arranged in the path of travel of the cam-shaped ends of the stem so that when the stems move vertically, the latches will be moved laterally out of the path of the top bar.

In the operation of the pressure release as 35 herein shown and described, assuming that the clothes wringer is in the position as shown in Figs. 1, 2 and 3, with the latches in engagement with the top bar, if a foreign 40 object or the operator's hand is accidentally drawn between the pressure rolls, the upper pressure roll is moved vertically beyond the ordinary distance it travels in allowing 45 clothes to pass between the pressure rolls, and the stem of the caps are carried upwardly such a distance that the cam faces thereof are brought into engagement with the cam lips of the pivoted latches so as to force the latches laterally out of the path of 50 travel of the movably mounted top bar which instantaneously releases the pressure means by allowing the top bar to move vertically.

I claim:

1. A clothes wringer, comprising a frame 55 having pressure rolls and pressure means for said rolls mounted therein, movable members carried by said frame for normally holding said pressure means in predetermined position, and members actuated by 60 the separation of said pressure rolls engaging said movable members for moving said movable members in position to release said pressure means.

2. A clothes wringer, comprising a frame 65 having pressure rolls and pressure means for

said rolls mounted therein, movable members for normally holding said pressure means in predetermined position, and members carried by the shaft of the upper pressure roll engaging said movable members for releasing said pressure means.

3. A clothes wringer, comprising a frame having pressure rolls and pressure means for said rolls, a top bar movably mounted within said frame having pressure screws 75 for adjusting said pressure means, movable members for holding said top bar in predetermined position within said frame, and members carried by the upper pressure roll shaft engaging said movable members for 80 releasing said pressure means.

4. A clothes wringer, comprising a frame having pressure rolls and pressure means for said rolls mounted therein, a top bar movably mounted in said frame having means 85 for adjusting said pressure means, plates carried by the side bars of said frame, pivoted members carried by said plates engaging said top bar for holding said top bar in predetermined position within said frame, said 90 pivoted members having cam portions, and a bifurcated stem embracing said pivoted members having cam portions co-acting with the cam portions of said pivoted members actuated by the abnormal separation of said 95 rolls for moving said pivoted latches out of engagement with said top bar for releasing said pressure means.

5. A clothes wringer, comprising a frame having pressure rolls and pressure means for 100 said rolls, spring actuated retaining members for normally holding said pressure means in predetermined position, and members actuated by the vertical movement of one of said pressure rolls engaging said retaining members for releasing the pressure 105 on said rolls.

6. A clothes wringer, comprising a frame having pressure rolls and pressure means for 110 said rolls mounted therein, a top bar movably mounted in said frame having means for adjusting said pressure means, movably mounted latches carried by the side bars of said frame for holding said top bar in predetermined position therein, and members 115 arranged in the path of travel of the upper pressure roll engaging said movable members on the abnormal separation of said rolls for moving said movable members out of engagement with said top bar for releasing 120 said pressure means.

7. A clothes wringer, comprising a frame having pressure rolls and pressure means for said rolls mounted therein, a top bar movably mounted within said frame having 125 means for adjusting said pressure means, pivoted latches carried by the side bars of said frame for holding said top bar in predetermined position within the frame, and members carried by the upper pressure roll 130

shaft engaging said latches for moving said latches out of the path of travel of said top bar.

8. A clothes wringer comprising a frame having pressure rolls and pressure means for said rolls mounted therein, pivoted spring actuated latches carried by the side bars of said frame for holding said pressure means in predetermined position therein, and members carried by the upper pressure roll shaft engaging said pivoted latches for releasing said pressure means.

9. A clothes wringer, comprising a frame having pressure rolls and pressure means for said rolls mounted therein, a top bar having means for adjusting said pressure means, retaining members for holding said top bar in predetermined position within said frame, and members actuated by the vertical movement of one of said pressure rolls engaging said retaining members for moving said retaining members out of the path of travel of said top bar for releasing said pressure means.

25 10. A clothes wringer, comprising a frame having slotted side bars, pressure rolls and pressure means for said rolls mounted in said frame, a top bar slidably mounted within the slotted side bars, means carried by said top bar for adjusting said pressure means, spring actuated member carried by the side bars engaging said top bar for holding said top bar in predetermined position within said frame, and members actuated by the vertical movement of the upper pressure roll for moving said spring actuated members out of the path of travel of said top bar for releasing said pressure means.

11. A clothes wringer comprising a frame having pressure rolls and pressure means for said rolls mounted therein, pressure screw carrying members movably mounted in said frame, movable members carried by the side bars of said frame for holding said pressure screw carrying members in predetermined position therein, and members carried by the upper pressure roll shaft engaging said movable members for moving said members out of the path of travel of said pressure screw carrying members.

12. A clothes wringer, comprising a frame having slotted side bars, bearings slidably mounted within said slotted side bars, shafts mounted in said bearings carrying pressure rolls, a top bar movably mounted within said side bars, pressure means disposed between said top bar and bearings including a pressure bar, and a bar carrying a spring engaging said pressure bar, a sliding connection between said top bar and spring carrying bar, means carried by said top bar for adjusting said pressure means, spring actuated members for holding said top bar in predetermined position within said frame, and members actuated by the vertical movement of the

upper pressure roll engaging said spring actuated members for moving said members out of engagement with said top bar for releasing said pressure means.

13. A clothes wringer, comprising a frame having pressure rolls and pressure means for said rolls mounted therein, a top bar movably mounted in said frame having means for adjusting said pressure means, plates carried by the side bars of said frame provided with guideways, pivoted latches carried by said plates engaging said top bar, and members carried by the upper pressure roll shaft engaging said latches for moving said latches out of the path of travel of said top bar on the vertical movement of said upper pressure roll.

14. A clothes wringer, comprising a frame having pressure rolls and pressure means for said rolls, a movably mounted top bar mounted in said frame having means for adjusting said pressure means, plates carried by the side bars of said frame having guideways, latches carried by said plates for holding said top bar in predetermined position within said frame, members carried by the upper pressure roll shaft slidably mounted within the guideways of said plates and engaging said latches for moving the said latches out of the path of travel of said top bar on the vertical movement of said pressure roll.

15. A clothes wringer, comprising a frame having pressure rolls and pressure means for said rolls mounted therein, shafts upon which said pressure rolls are mounted, a top bar movably mounted in said frame having means for adjusting said pressure means, pivoted latches carried by the side bars of said frame for holding said top bar in predetermined position within said frame, caps carried by the shaft of the upper pressure roll, and stems carried by said caps engaging said latches on the upward movement of said pressure roll for releasing said pressure means.

16. A clothes wringer, comprising a frame having slotted side bars, shafts mounted in said frame carrying pressure rolls, pressure means for said rolls mounted in said frame, a top bar movably mounted in said frame having means for adjusting said pressure means, movable latches carried by the side bars of said frame for holding said top bar in predetermined position within said frame, and members carried by the shaft of the upper pressure roll engaging said latches on the upward movement of said roll for releasing said pressure means.

17. A clothes wringer comprising a frame having slotted side bars, bearings mounted in the slots of said side bars, shafts mounted in said bearings carrying pressure rolls, a top bar movably mounted in said frame, plates carried by the side bars of the said

frame, spring latches carried by said plates for holding said top bar in predetermined position within said frame, pressure means mounted in said frame for said rolls, pressure screws mounted in the top bar for adjusting said pressure means, and members carried by the shaft of the upper pressure roll engaging said latches for moving said latches out of the path of travel of the top bar for releasing said pressure means.

18. A clothes wringer, comprising a frame having pressure rolls and pressure means for said rolls mounted therein, a top bar movably mounted within said frame having means for adjusting said pressure means, plates carried by the side bars of said frame provided with guideways, pivoted latches mounted on said plates for holding said top bar in predetermined position within said frame, said latches being provided with cam portions, and members carried by the shaft by the upper pressure roll working in said guideways having cam portions coacting with the cam portions of said latches for moving said latches out of the path of travel of said top bar on the upward movement of said pressure roll.

19. A clothes wringer, comprising a frame having slotted side bars, pressure rolls and pressure means for said rolls mounted with-

in said frame, a top bar movably mounted within said frame having means for adjusting said pressure means, spring latches for holding said top bar in predetermined position within said frame, and members carried by the upper pressure roll shaft engaging said latches for moving said latches out of the path of travel of said top bar for releasing said pressure means.

20. A clothes wringer, comprising a frame having slotted side bars, pressure rolls mounted in said frame, pressure means for said rolls, a top bar movably mounted in said frame having means for adjusting said pressure means, pivoted latches carried by the side bars for holding said top bar in predetermined position within said frame, said latches being provided with cam portions, springs for holding said latches in engagement with said top bar, and members carried by the upper pressure roll shaft having cam portions coacting with the cam portions of said latches for moving said latches out of the path of said top bar on the upward movement of said pressure roll.

In testimony whereof I hereunto affix my signature in the presence of two witnesses.

JOHN F. HEMENWAY.
